FIRE EXTINGUISHER

Charles A. Thomas and Carroll A. Hochwalt,
Dayton, Ohio, assignors to The Fyr-Fyter Company, Dayton, Ohio, a corporation of Ohio

No Drawing. Application April 10, 1928,
Serial No. 269,018

8 Claims. (Cl. 23—9)

This invention relates to the extinguishing of fires.

It is among the objects of this invention to provide a fire-extinguisher charge which has superior fire-extinguishing properties, and sufficient to meet the present requirements for such extinguishers; and this invention is in the nature of a discovery disclosing particular compounds which involve a certain group of elements which compounds we have found to possess unusual or special advantages from the fire-extinguishing standpoint.

Another object of this invention is to provide a novel method of extinguishing fires which is highly effective for extinguishing both wood and oil fires.

Other objects and advantages of this invention will be apparent from the following disclosure.

Combustion or active burning is a chemical reaction, and obeys the general laws governing such reactions. Ordinary fire is combustion out of control. The method of fire extinguishing heretofore used involves either the cooling of the burning material below its kindling point, or the smothering of the fire by the exclusion of air or oxygen from the combustion zone.

The present invention provides a novel method of extinguishing fires which is highly effective and superior to the methods heretofore used. This method involves the introduction upon the fire of a compound which has what may be termed a high "negative-catalytic" effect upon combustion. This effect tends to inhibit combustion, or the tendency of the materials to react, as distinguished from a cooling or smothering effect. We have discovered that certain compounds involving a certain group of elements possess this negative-catalytic effect, and provide superior fire-extinguishing mediums. In detail, we have discovered that those alkali metal elements which are contained in group I of the periodic table of elements, namely lithium, sodium, potassium, rubidium and caesium, when combined with a radical to form a compound, present a group of substances which prove upon test to have peculiarly advantageous fire-extinguishing properties.

We have still further discovered that the degree of effectiveness of the fire-extinguishing compound depends upon the particular character of the radical combined with the alkali metal element.

We have further discovered that in this group of alkali metals, for the extinguishing character-

istics referred to, some of the metals of this group are superior to others. For example, those having the heavier atomic weights have a general superiority over those having the lighter atomic weights. Specifically we have found that potassium, rubidium and caesium when combined with a radical referred to, have relatively the more pronounced fire-extinguishing effect; whereas sodium and lithium have a poorer effect.

Reference is herein made to the copending application of Charles A. Thomas and Carroll A. Hochwalt, Serial No. 257,400, filed February 27, 1928, now Patent 1,895,530, in which are disclosed compounds of alkali metal elements of group I of the periodic table having exceptional or superior fire-extinguishing characteristics. These compounds are applicable for use in carrying out the method of the present invention.

We have also discovered that the negative-catalytic effect upon combustion or the exceptional fire-extinguishing effect of these compounds is superior within a certain temperature range, which range may vary somewhat for different compounds. We have found, for example, that the negative-catalytic effect in general is superior within a temperature range of 175° C. to 325° C. In testing these various compounds, dilute water solutions of the compounds were prepared in order to determine the lowest concentration of a solution which would put out a standard test fire. It was at these low concentrations that the temperature effect was noticeable. The standard test fire was generally prepared by igniting gasoline contained within a small pan, and the extinguishing effect of the various compounds determined by projecting various concentrations of these compounds upon the oil fire to determine the lowest concentration which would put out this standard test fire. The temperature of the side of the pan above the gasoline level was determined by a potentiometer. It was found that when such dilute solutions were projected on a fire where the temperature of the wall of the pan was above the range specified, the temperature first dropped to within the effective temperature range and then the fire would go out.

From the results obtained with the test fire, it is believed that the extinguishing action of such a solution upon an actively burning fire where the temperature is higher than the range above specified, is substantially as follows. First there is a lowering of the temperature of the combus-

tion to within the highly effective temperature range of the fire-extinguishing compound, where the compound then exhibits its strongest negative-catalytic effect upon combustion to extinguish the fire. For accurately comparing the fire-extinguishing effects of various compounds in very dilute water solutions an average temperature of the wall of the test pan of 270° C. gave very satisfactory results.

10 Where there is a high concentration of a compound of an alkali metal having superior fire-extinguishing properties in the solution, the fire is extinguished under all conditions. In general, it may be said that the fire-extinguishing 15 properties of a water solution of any one of these superior fire-extinguishing compounds mentioned above increases with the concentration of the solution up to a point of high concentration. In actual fire-extinguishing practice, it is 20 desirable to have the fire-extinguishing solutions sufficiently concentrated to get the best extinguishing effects, such for example as a concentration in excess of 15% by weight of the compound. High solubility of a compound is 25 an advantage, for this permits a high concentration of the alkali metal compound to be placed in the solution with increased extinguishing effect. Actual tests have shown that sufficiently concentrated water solutions of these 30 compounds above mentioned having superior fire-extinguishing properties, and particularly water solutions of compounds of potassium, rubidium and caesium, provide extinguishing mediums which are as effective on oil fires as carbon tetrachloride, and which unlike carbon tetrachloride do not give off obnoxious fumes when used on the fire; and at the same time these 35 solutions are also applicable to general fires or wood fires and are more effective on such wood fires than any extinguisher charge here- 40 tofore known.

In the extinguishing of oil tank fires, the best results are obtained by projecting a solution of a compound of an alkali metal element having high fire-extinguishing properties across and above the seat of combustion in a manner to impinge the solution upon the far inner wall of the tank containing the burning oil, producing a fine spray of the solution above the seat of combustion.

50 We have further discovered that among these compounds of the alkali metal elements having high fire-extinguishing properties, those in which the alkali metal element is combined with an oxygen bearing radical are in general the most effective.

We have further found that of the inorganic compounds, in general the oxidizing compounds of the alkali metal elements are superior and provide highly effective fire-extinguishing 60 mediums. Thus, a compound comprising an alkali metal element of group I combined with a chromate radical or a dichromate radical, such as sodium dichromate or potassium dichromate, provides a superior fire-extinguishing agent. We have also discovered that when these elements are combined with other oxidizing radicals such as the permanganate radical, superior 65 fire-extinguishing compounds, such as potassium permanganate for example, are provided.

70 It is also true, according to our discovery, that in addition to the oxidizing compounds mentioned, other oxidizing compounds such as those involving radicals containing a halogen and oxygen are highly effective fire-extinguishing 75

agents. For example, the chlorate, bromate and iodate of the alkali metals are excellent fire-extinguishing compounds. In general, the higher the percentage of oxygen in the molecule of these compounds, the superior the extinguishing effect. For example, the perchlorate of potassium is found to be even superior to the chlorate of potassium. 5

We have also discovered that sodium potassium carbonate dissolved in sufficient concentration in water possesses these superior fire-extinguishing properties and provides an effective fire-extinguishing medium. 10

The general superiority of compounds containing an oxygen bearing radical, or a high 15 percentage of oxygen in the molecule is also exemplified in certain organic compounds. For example, potassium tartrate is found to be an excellent fire-extinguishing medium; but the bitartrate of potassium is found to be even superior to the tartrate of potassium, both being 20 organic compounds of an alkali metal element of group I and having superior fire-extinguishing properties. 25

We have also discovered by these investigations, that these alkali metal elements above mentioned combined with an aromatic organic radical provide compounds having superior fire-extinguishing properties. Thus, a compound 30 having an aromatic carboxylic acid radical, such as the gallate which is an aromatic trioxymono-carboxylic acid radical, has these exceptional fire-extinguishing properties when combined with an alkali metal element such as potassium.

It has also been found that amino compounds of these alkali metals, such as potassium anthranilate which is an aromatic amidomono-carboxylic acid radical, have these superior fire-extinguishing properties. 35

In referring above and in the claims to the 40 superior or exceptional fire-extinguishing characteristics of these various substances, we mean in comparison with the present-day requirements and conditions which have to be met in the specified tests outlined by Underwriters' 45 Laboratories. An example of such a requirement or test is what is termed the "partition test fire". The partition used in this test comprises a wooden decking 10' square made of tongue and groove pine flooring, onto which is 50 nailed four layers of 1" x 1" dressed spruce strips 10' long. In the first layer, the strips are placed 12" apart. The second layer running at right angles to the first layer has the strips 1" apart. The third layer running at 55 right angles to the second layer has the strips 12" apart. The fourth layer running at right angles to the third layer has the strips 1" apart. This completed partition sample has five gallons of fuel oil evenly sprinkled over the lattice work 60 surface. The sample is then fastened in a vertical position, and a quantity of excelsior is placed along the lower edge and ignited. At regular intervals three additional supplies of excelsior are pushed up to feed the fire. After 65 the fire has burned five or six minutes, or until some of the strips begin to break, the extinguisher is applied. The time for extinguishment is taken at the time all flame disappears. Using a ten quart conventional soda and acid charge, 70 this fire generally requires on an average about thirty-five seconds to be extinguished,—almost invariably over twenty-five seconds. Conventional types and sizes of carbon tetrachloride extinguishers are found to be totally ineffective 75

on this type of test fire. However, using only seven quarts of a water solution containing a relatively high concentration, such as in excess of 15% by weight, of an alkali metal compound having the exceptional fire extinguishing properties of the present invention, the solution exhibiting the unusual negative catalytic effect upon combustion characteristic of the mediums of the present invention, this standard partition test fire is readily extinguished in considerably less than twenty-five seconds, often in as short a time as nine to ten seconds.

While the materials and compositions herein described constitute preferred embodiments of our invention, it is to be understood that the invention is not limited to these precise materials and compositions, and that changes may be made without departing from the scope of our invention as defined in the appended claims.

20 What is claimed is:

1. The method of extinguishing oil tank fires which comprises projecting an aqueous solution of high concentration of a compound of an alkali metal element of group I of the periodic 25 table of elements having high fire-extinguishing properties, across and above the seat of combustion in a manner to impinge the solution upon the far inner wall of the tank, whereby a fine spray of the solution is produced above the seat 30 of combustion.

2. The method of extinguishing an oil tank fire which comprises projecting a relatively concentrated aqueous solution of a compound of potassium having inherently exceptional fire ex-

tinguishing properties in the form of a fine spray immediately above the seat of combustion of the tank fire, the solution having a highly effective negative catalytic effect upon combustion, and being capable of extinguishing a standard partition test fire, when applied in the usual test quantities or less, in less than twenty-five seconds.

3. The method in the extinguishing of fire, which comprises projecting upon the fire a solution of an alkali metal salt of an amido-carboxylic acid.

4. The method in the extinguishing of fire, which comprises projecting upon the fire a water solution of an alkali metal salt of an aromatic 15 amido-carboxylic acid.

5. The method in the extinguishing of fire, which comprises projecting upon the fire a water solution of potassium anthranilate.

6. The method in the extinguishing of fire, 20 which comprises projecting upon the fire a solution of high concentration of an amino compound of an alkali metal element, the solution characterized by a negative catalytic effect upon combustion.

7. The method in the extinguishing of fire, which comprises projecting upon the fire a solution of a compound of an alkali metal element combined with an anthranilate radical.

8. The method in the extinguishing of fire, 30 which comprises projecting upon the fire a solution of an alkali metal gallate.
